UNITED STATES PATENT OFFICE.

PETER MAZIARZ, OF PAWTUCKET, RHODE ISLAND.

WIRE-CUTTING WEAPON.

1,282,903.

Specification of Letters Patent. Patented Oct. 29, 1918.

Application filed July 22, 1918. Serial No. 246,063.

To all whom it may concern:

Be it known that I, PETER MAZIARZ, a subject of the Emperor of Austria, residing at Pawtucket, in the county of Providence and 5 State of Rhode Island, have invented certain new and useful Improvements in Wire-Cutting Weapons, of which the following is a specification.

The primary object of the invention is the 10 provision of a wire cutter that is compact in form positioned substantially inclosed within the handle of a knife or sword and readily operable for severing wires whenever desired.

15 A further object of the invention is the provision of a wire cutter carried by a sword handle and normally closed within the handle, the same being adapted for automatic positioning ready for use in cutting wires 20 when the device is released by the operator.

A still further object of the invention is to provide means for cutting barbed and similar wires such as wire entanglements 25 upon the line of march, the device being compactly carried by the handle of a cutting blade without interfering with the ordinary use of the blade or adding materially to the weight of the weapon.

With these general objects in view, the 30 device will be fully described in connection with the accompanying drawings and in which like designating characters refer to corresponding parts throughout the several views.

35 In the drawings,

Figure 1 is a central longitudinal sectional view of the device with the blade broken away with the device in its open position;

40 Fig. 2 is a similar view of the same with the device closed;

Fig. 3 is an elevational view of one side of the device;

45 Fig. 4 is a similar view of the opposite side of the same;

Fig. 5 is an end view of the device open; and

50 Figs. 6 and 7 are transverse sectional views taken upon lines VI—VI and VII—VII respectively of Fig. 1.

It will be understood that my wire cutter is adapted for employment with the handle or shank of any form of blade such as a bayonet or sword and the same is herein set

forth by way of illustration installed upon 55 the handle 10 of a two-edged blade 11. The handle 10 has an internal chamber 12 open at one side of the handle in the form of a longitudinal slot 13 while the blade 11 is secured in a socket 14 in one end 15 of the 60 handle for projecting in longitudinal alignment therewith by means of rivets 16.

An offset 17 laterally projects from the handle end 15 provided with a recess 18 adapted to receive a cutting block 19 having 65 a shank 20 slidably mounted in a passageway 21 longitudinally of the handle 10 adjacent the closed side of the chamber 12. A spring 22 is positioned within said chamber having one end seated in a pocket 23 adjacent the butt end 24 of the handle 10 while the other end of said spring is mounted upon a lug 25 at the inner end of the shank 20. The spring 22 is adapted to force the block 19 out of the recess 18 while one side of the 70 recess is provided with a sharpened edge 26 adapted for severing wires positioned between the block 19 and offset 17 during the closing or seating of the block within said recess 18.

An operating lever 27 is adapted for swinging movement within the slot 13 being pivoted therein by means of a rivet 28. An angular extension 29 of said lever is pivotally connected by means of a link 30 with a 85 plate 31 pivoted in the chamber 12 upon a rivet 32 adjacent the lower open end of the passageway 21. The other end of the plate 31 is positioned in a slot 35 adjacent the lower end of the shank 20 being loosely pivoted by means of a slot 33 in the said plate upon a pin 34 carried by the shank transversely of the slot 35.

When the shank 20 is projected with the 90 block 19 in its open position, the lever 27 extends obliquely from the handle 10 as illustrated in Fig. 1 of the drawings. Upon forcing said lever 27 toward the handle 10 and inwardly of the slot 13, the shank 20 is retracted and the block 19 forced inwardly of the recess 18 cutting any wires which have been positioned upon the offset 17 at the end 15 of the handle. A latch hook 36 is pivoted within the chamber 12 having its inturned end 37 normally positioned by means of a spring 38 in the closing path of movement of the notched free end 39 of the lever 27. Upon closing the 100

said lever inwardly of the slot 13, the hook 37 of the latch engages the notch 39, thereby retaining the device closed with the block 19 in the recess 18. A releasing plunger 40 slidably extends through the butt 10 pivoted within the chamber 12 of the latch 36 and provided with a button 41, upon its outer end and whereby upon inwardly pressing the button 41, the latch 36 is released from the lever 37 and the spring 32 automatically swings said lever to its open position with the shank 20 projected and the block 19 separated from the cutting edge 26.

15 A lateral opening 42 is provided in one side of the handle 10 for convenience in assembling pin 34 for connecting shank 20 and plate 31 pivotally together, while a threaded plug 43 is fitted within the said 20 opening for normally closing the same. When the lever 27 is closed, the handle may be readily grasped by one or both hands of the operator for wielding the blade 11 while the offset 17 and a projecting lip 44 at the 25 opposite side of the handle end 15 serve as a manner of pommel or guard during such use of the device. The block 19 is instantly opened automatically ready for use by means of the spring 22 when the button 41 30 is pressed inwardly and the wire cutting attachment may be employed with many different forms of knives and cutters.

What I claim as new is:—

1. In combination with a knife handle 35 having a chamber therein opening in a slot longitudinally of the handle, a cutting member shiftably carried by the handle having a portion extending within said handle, an operating lever for said cutting member 40 pivoted for swinging outwardly and inwardly of said slot, operative connections between said lever and said cutting member, and a spring within said chamber engaging said cutting member adapted for 45 automatically positioning said member and the said lever in their open positions.

2. In combination with a knife handle having a chamber therein opening in a slot longitudinally of the handle, a cutting member shiftably carried by the handle having a portion extending within said handle, an operating lever for said cutting member pivoted for swinging outwardly and inwardly of said slot, operative connections 50 between said lever and said cutting member, a spring within said chamber engaging said cutting member adapted for automatically positioning said member and the said lever in their open positions, a spring- 55 pressed retaining latch pivoted within said chamber adjacent the butt end of the handle adapted for automatically retaining said lever in its closed position within said slot when the cutting member is in its retracted 60 closed position, and releasing means for said 65

latch extending outwardly of said butt end of the handle.

3. A wire cutter for a knife handle comprising in combination with a lateral recess at one end of the handle having a sharpened cutting blade, a cutting block adapted for seating within said recess provided with a shank portion slidably carried by the handle, a spring engaging said shank portion adapted for automatically projecting 75 said block outwardly of the recess for the reception of a wire to be cut between said block and cutting edge, manually operable retracting means for the said block attached to the shank portion thereof, and 80 a retaining latch for said operating means carried by the handle adapted for automatic engagement with said operating means when the block is seated within the said recess.

4. A wire cutter for a knife handle comprising in combination with a lateral recess at one end of the handle having a sharpened cutting blade, a cutting block adapted for seating within said recess provided with a shank portion slidably carried by the handle, a spring engaging said shank portion adapted for automatically projecting said block outwardly of the recess for the reception of a wire to be cut between said block and cutting edge, a plate pivotally mounted 95 upon said handle operatively connected to the shank of said block, an angular operating lever for the block at the opposite side of the handle therefrom, and a link pivotally connected between the adjacent ends of 100 said plate and lever.

5. A wire cutter for a knife handle comprising in combination with a lateral recess at one end of the handle having a sharpened cutting blade, a cutting block 105 adapted for seating within said recess provided with a shank portion slidably carried by the handle, a spring engaging said shank portion adapted for automatically projecting said block outwardly of the recess for 110 the reception of a wire to be cut between said block and cutting edge, a plate pivotally mounted upon said handle operatively connected to the shank of said block, an angular operating lever for the block at 115 the opposite side of the handle therefrom, a link pivotally connected between the adjacent ends of said plate and lever, a spring-pressed latch pivoted upon said handle having a hooked end, the said lever having a 120 notched free end adapted for automatic engagement with the hooked end of the latch when the block is closed within said recess, and releasing means for said latch projecting outwardly of the butt end of 125 said handle.

6. In combination with a knife handle having a chamber therein opening in a slot longitudinally of the handle, a cutting member shiftably carried by the handle 130

having a portion extending within said handle, an operating lever for said cutting member pivoted for swinging outwardly and inwardly of said slot, operative connections between said lever and said cutting member, a spring within said chamber engaging said cutting member adapted for automatically positioning said member and

the said lever in their open positions, the said handle having a threaded opening 10 through the side thereof communicating with the point of attachment of said operative connections, and a closure plug normally positioned within said opening.

In testimony whereof I affix my signature. 15
PETER MAZIARZ.
